UNITED STATES PATENT OFFICE

ADOLF WELTER, OF KREFELD-RHEINHAFEN, GERMANY

COMPRESSED AIR SOAP

Application filed May 2, 1929, Serial No. 360,008, and in Germany October 31, 1928.

The present invention relates to an improved process for preparing soap powder from liquid grain soap.

It has hitherto been usual to produce soap powder from liquid grain soap by heating the latter in a closed vessel (autoclave) to a temperature exceeding 100° C., and then supplying the liquid grain soap under the pressure prevailing in the vessel to any atomizing apparatus. Naturally, the soap solution is the more thinly liquid and, accordingly, the atomization is the better, the higher the pressure prevailing in the vessel and therefore the temperature producing it. In order to secure these favorable conditions as much as possible, steam for example has been injected into the pressure vessel. However, the soap solution was so much diluted by this that the atomization was not effected advantageously. Again, instead of injecting steam, the vessel containing the liquid grain soap has been heated by means of heating devices from the exterior, i. e. by heating devices from which no steam could enter the vessel. However, the soap on the walls of the vessel then became so strongly heated, that solid masses (incrusted) set on the walls, which masses acted, so to speak, as heat insulators, and caused considerable waste of heat. This became very apparent, and was very disadvantageous particularly when filled soaps, i. e. soaps mixed with other additions such as, for example, water-glass, were treated.

A further disadvantage also was that only large vessels could be used for working in, since only then could a uniform pressure be ensured, which is necessary for a good atomization. In this case, however, too great a space remains free over that part of the vessel filled with liquid, into which too much steam could escape from the liquid contents of the vessel. This loss of steam concentrated the liquid too much, so that its drying up and therefore the formation of incrusted was very much favored.

It has now been found that soap powder may be produced by the direct atomization of liquid grain soap easily and advantageously, i. e. without too great an expenditure of

heat, if the process is carried out so that no appreciable quantities of solid material can deposit on the inner walls of the pressure vessel during the heating of the grain soap in the latter vessel. More particularly filled soaps may be advantageously treated in this way. By "filled soap" is meant any soap which contains one or several of the fillers known in the art, e. g. water-glass, soda, potash, borax, salts of phosphoric acid, clay, Fullers' earth, etc.

According to this invention the formation of incrusted is prevented by adding to the liquid soap being treated solid salts which have a salting-out effect, such as common salt or caustic alkali and injecting a highly compressed gaseous medium in the space above the liquid soap. The space over the liquid which is filled with the gaseous medium is preferably kept as small as possible, so that only a small amount of gaseous medium will be required. During the injection of the gaseous medium the mixture in the vessel is heated above 100° C. and allowed to settle, so that brine separates below and thinly liquid grain soap above, which latter is then atomized.

Instead of solid salt, concentrated brine, or a mixture of solid salt and brine or caustic alkali lyes may also be used. As gaseous media may be used steam or a noncondensable gas, such as air. When steam is employed it is preferably used as highly compressed and as superheated as possible. The vessel is being heated during the injection and under these conditions the amount of water which condenses is insufficient to dilute the soap lye excessively and therefore produce the mentioned disadvantages. However, it is not essential that the steam should be superheated, and when employing air it is not necessary to heat the latter at all.

Naturally solid salt or brine, or other salts, such as, for example, Glauber's salt, sodium phosphate, potassium chloride, potassium acetate, etc., may be added when no steam is injected, more particularly when a non-condensing gas is injected in the space over the liquid. The following examples indicate the

manner in which the invention is carried out.

Examples

1. Liquid grain soap with a fatty acid content of 60-64%, contained in a closed vessel, is mixed with the requisite quantity of solid common salt. By means of a steam coil at the bottom of the vessel, steam is led into the interior of the vessel, until a pressure of about 4 to 10 atmospheres is attained. The vessel is then allowed to stand for a short time and the grain soap, which meanwhile has separated from and lies on the surface of the brine, is led to the atomizing nozzles under the pressure prevailing in the vessel.

2. Liquid grain soap contained in a closed vessel is floated on a layer of hot, saturated common salt solution. The vessel is now heated by direct firing, or else by steam pipes, running through the interior of the vessel or situated in the walls of the vessel, which do not allow any steam to get into the interior of the vessel. Simultaneously compressed air at 10 to 14 atmospheres pressure is pumped into the space above the liquid in the vessel. When a temperature of about 175° C. is reached, the vessel is allowed to stand for a short time, and then the thinly liquid grain soap floating about on the surface is forced to the atomization apparatus.

I do not intend to limit myself in any way whatsoever to the details mentioned in the foregoing description and examples with regard to the methods of working, the temperatures, pressures, mixtures, heating devices, etc. Every working procedure and accessory thereto, in which soap powder is prepared from liquid grain soap, more particularly from filled grain soap, in such a way that the grain soap is heated in a closed vessel to a temperature above 100° C. with employment of the said means for preventing solid masses or crusts from setting on the walls of the vessel during the said heating, and the thinly liquid grain soap, while still hot, is then supplied to an atomizing device by the pressure prevailing in the vessel and is thus converted, by means of a known atomization process, into soap powder, is to be regarded as coming within the scope of the present invention. In this way a dry non-caking powder is formed against an opposed current of air by means of any atomization apparatus; the air current need be only comparatively weak and, also, need not be warmed. Since the heat content necessary for vapourizing the water contained in the atomized soap is, in the process which is the subject of the present invention, already present in the hot soap mass to be atomized, it is not necessary, therefore, to supply it separately.

More particularly is it to be remarked, that the heating of the pressure vessel may be

produced by any means, e. g. from the exterior by direct firing, by an oil- or metal-bath, by a steam jacket, by tubes enclosed in or welded on the walls (on the casing), heated by steam, hot water under pressure, or hot oil. Also heating elements of any kind may be built or suspended within the vessel in the liquid. Also, in order to improve the heat distribution, a stirring mechanism of any kind may be arranged in any manner.

In the accompanying drawings, apparatus suitable for carrying out the present invention is shown schematically and by way of example.

Figure 1 shows a constructional form in which liquid grain soap and salt liquor are simultaneously pumped into the autoclave. After closing the autoclave the mixture is heated by the steam jacket. When the required high temperature is attained the stirring mechanism is stopped and the mixture allowed to settle. First of all the salt liquor is pressed out through the bottom cock then the hot grain soap now in the vessel is supplied to the atomization apparatus either by means of the intrinsic pressure or better with the assistance of compressed air.

In Fig. 2 the heating is not effected by means of a double jacket but the liquid grain soap is directly pumped into the vessel and floated on a layer of saturated salt solution. The direct firing may be accomplished by means of a coal fire or oil bath, or by means of gas, or otherwise as hereinbefore stated.

Fig. 3 shows a constructional form in which the heating apparatus lies in the lower part of the pressure vessel. Liquid grain soap is pumped in and at the same time about 5-6% of solid salt is added. Then steam is blown through an upright tube into the salt until the desired high pressure is attained; owing to the water of condensation which is formed the salt dissolves to a salt liquor. The steam and the heating apparatus are shut off and first of all the salt liquor is forced out through the steam leading-in pipe owing to the internal pressure or better by means of compressed air, then the hot liquid grain soap is forced out to the atomization apparatus. In place of solid salt, salt liquor may be used here, which is then heated by means of a worm. This heating may also be assisted by the direct introduction of steam.

Generally it must be mentioned in this connection that instead of pumping ready prepared liquid grain soap into the pressure vessel it may first of all be produced in the same, and further that a stirring mechanism is not absolutely necessary but only assists the better conduction of heat. By operating in such a way all incrustation is avoided, and the heat conduction is so good that the tem-

perature is produced in a fraction of the time which is necessary when salt or salt liquor are not used.

In Fig. 1, 1 is a pressure vessel with an inner vertical shaft 2 for the stirring mechanism 3. The mechanism for driving the stirring device is indicated with 4. 5 is a device for introducing liquid soap, as well as salt in solid form or in the form of concentrated 10 solutions. 6 is a de-aerating cock, 7 is the draining cock, 8 is the steam jacket, 9 is the pipe for the fresh steam, 10 is the drain for the water of condensation.

In Fig. 2 instead of effecting the heating 15 by means of the steam jacket 8, heating is effected by means of the heating furnace 11 having a fire 12 and flues 13.

According to Fig. 3 the heating is not effected from the exterior but is carried out by 20 means of the heating worm 14 situated inside, and instead of the stirring mechanism the pipe 15 is arranged for blowing-in steam or compressed air. This pipe is also used at the same time for expelling under pressure.

25 I do not limit myself in any way to the use of an apparatus which corresponds exactly to the apparatus shown in the drawing, but the apparatus may be formed as desired within the scope of the purpose apparent from the invention.

What I claim is:

1. A process for producing soap powder from liquid grain soap which comprises heating by an external source liquid grain soap in 35 an enclosed space to a temperature exceeding 100° C. in presence of salts capable of producing a salting-out effect, and simultaneously injecting under high pressure a gaseous medium into the portion of the enclosed space 40 above the liquid soap, then allowing the liquid soap to collect, and atomizing the same under the pressure prevailing in the enclosed space.

2. A process for producing soap powder from liquid grain soap which comprises heating by an external source liquid grain soap in 45 an enclosed space to a temperature exceeding 100° C. with concentrated brine, and simultaneously injecting under high pressure a non-condensable gas into the portion of the enclosed space above the liquid soap, then allowing the liquid soap to collect, and atomizing the same under the pressure prevailing in the enclosed space.

3. A process for producing soap powder 55 from liquid grain soap which comprises heating by an external source liquid grain soap in an enclosed space to a temperature exceeding 100° C. with concentrated brine, and simultaneously injecting air into the portion 60 of the enclosed space above the liquid soap, then allowing the liquid soap to collect, and atomizing the same under the pressure prevailing in the enclosed space.

4. A process for producing soap powder 65 from liquid grain soap which comprises heat-

ing by an external source liquid grain soap in an enclosed space to a temperature exceeding 100° C. with solid salts capable of producing a salting-out effect, and simultaneously injecting highly compressed steam into the portion of the enclosed space above the liquid soap, then allowing the liquid soap to collect, and atomizing the same under the pressure prevailing in the enclosed space.

5. A process for producing soap powder 70 from liquid grain soap which comprises heating by an external source liquid grain soap in an enclosed space to a temperature exceeding 100° C. with concentrated brine, and simultaneously injecting highly compressed steam into the portion of the enclosed space above the liquid soap, then allowing the liquid soap to collect, and atomizing the same under the pressure prevailing in the enclosed space.

6. A process for producing soap powder 75 from liquid grain soap which comprises heating by an external source liquid grain soap in an enclosed space to a temperature exceeding 100° C. with concentrated brine, and solid 80 salts capable of producing a salting-out effect, and simultaneously injecting highly compressed steam into the portion of the enclosed space above the liquid soap, then allowing the liquid soap to collect, and atomizing the same under the pressure prevailing in the enclosed space.

7. A process for producing soap powder 85 which consists in heating in a closed vessel a mixture of liquid grain soap having a fatty acid content of from 60 to 64% and a requisite quantity of common salt, by means of steam entering at the bottom of said closed vessel, until a pressure of from 4 to 10 atmospheres 90 is attained, then permitting the mixture to stand for a short time causing grains of soap to form and collect on top of the surface of the brine and conducting the grains while maintaining said pressure into an atomizing apparatus.

8. A process for producing soap powder 100 which consists in heating in a closed vessel a mixture of liquid grain soap having a fatty acid content of from 60 to 64% and a requisite quantity of common salt, by means of highly compressed steam forced into the mixture at the bottom of said vessel, until a pressure of from 4 to 10 atmospheres is attained, then permitting the mixture to stand for a short time causing grains of soap to 105 form and collect on top of the surface of the brine and conducting the grains while maintaining said pressure into an atomizing apparatus.

9. A process for producing soap powder 110 which consists in heating in a closed vessel a mixture of liquid grain soap having a fatty acid content of from 60 to 64% and a requisite quantity of common salt, by means of steam entering at the bottom of said closed 115 vessel,

vessel, until a pressure of from 4 to 10 atmospheres is attained, then permitting the mixture to stand for a short time causing grains of soap to form and collect on top of the surface of the brine and subsequently converting said grains of soap by atomization to powder while maintaining said pressure.

10. A process for producing soap powder which consists in heating in a closed vessel a mixture of liquid grain soap having a fatty acid content of from 60 to 64% and a requisite quantity of common salt, by means of highly compressed steam forced into the mixture at the bottom of said vessel, until a pressure of from 4 to 10 atmospheres is attained, then permitting the mixture to stand for a short time causing grains of soap to form and collect on top of the surface of the brine and subsequently converting to powder the grains of soap by atomization while maintaining said pressure.

In testimony whereof I have signed my name to this specification.
